L. H. BAYLER

VALVE SPRING LIFTER

Filed Jan. 23, 1925

Inventor:
Louis H. Bayler
By Hazard and Miller
Attorneys.

Witness:
H. Hall

UNITED STATES PATENT OFFICE.

LOUIS H. BAYLER, OF LOS ANGELES, CALIFORNIA.

VALVE-SPRING LIFTER.

Application filed January 23, 1925. Serial No. 4,225.

To all whom it may concern:

Be it known that I, LOUIS H. BAYLER, a citizen of the United States, residing at Los Angeles, in the county of Los Angeles and 5 State of California, have invented new and useful Improvements in Valve-Spring Lifters, of which the following is a specification.

This invention relates to improvements in 10 valve spring lifters, and is especially an improvement over the valve spring lifter disclosed in my prior Patent No. 1,445,609, issued February 13, 1923.

An object of this invention is to increase 15 the usefulness of the tool in such a manner that the tool may be applied to a large number of different types of engines for lifting the valve springs of these engines.

It is a further object of the invention to 20 provide a valve spring lifter which may be more easily and more quickly applied to an engine to lift the valve spring and which may be more easily withdrawn.

Other improvements and modifications 25 and other objects will be made manifest in the following detailed description and specifically pointed out in the appended claims, reference being had to the accompanying drawings for a disclosure of the improved 30 valve spring lifter, wherein:

Figure 1 is a side elevation of the improved valve spring lifter;

Fig. 2 is an end elevation of the valve spring lifter shown in Fig. 1;

Fig. 3 is a vertical section through the valve spring lifter taken substantially on the line 3-3 of Fig. 1;

Fig. 4 is an enlarged section illustrating a detail of construction;

Fig. 5 is a horizontal section illustrating one manner in which the spring engaging means may be attached to the yoke of the valve spring lifter;

Fig. 6 is a horizontal section illustrating 45 another manner in which the spring engaging means may be attached to the yoke;

Fig. 7 is a side elevation of the device disclosed in Fig. 6;

Fig. 8 is a horizontal section illustrating 50 a third manner in which the spring engaging means may be attached to the yoke of the lifter;

Fig. 9 is a side elevation of the device disclosed in Fig. 8;

Fig. 10 is a view taken substantially on 55 the line 10-10 of Fig. 7;

Fig. 11 is a view taken substantially on 60 the line 11-11 of Fig. 9; and

Fig. 12 is a top plan view of a modified 65 form of spring engaging means.

Referring to the accompanying drawings wherein similar reference characters designate similar parts throughout, the improved valve spring lifter consists of a yoke 10, somewhat U-shaped in form, and in cross section having the appearance similar to an eyebar. Upon the lower end of the yoke 10 there is detachably secured a spring engaging means, generally designated at 11. This spring engaging means is in the form 70 of a fork having upturned side and back edges 12 and 13 respectively. The fork is adapted to be placed about the valve stem V' of a valve V beneath the valve spring S, and the complete lifter is adapted to compress the spring S lifting the washer W so as 75 to permit withdrawal of the pin or key P from the valve stem V'.

In Figs. 5 to 11 inclusive I have disclosed 80 various means by which the fork or spring engaging means may be detachably secured to the yoke 10. In the preferred form of construction, the fork has rearwardly extending fingers 14 and 15, which are adapted to slide upon the opposite sides of a web 16 85 of the yoke 10. The top and bottom portions of the eyebar forming the yoke 10 prevent movement of the fingers 14 and 15 other than sliding upon the web 16. In the device shown in Fig. 5, I provide a thumb screw 17 which is adapted to be passed through the fingers 14 and 15 and through the web 16 so as to secure the fork to the yoke 10. In the device disclosed in Figs. 6 and 7, the fingers 14 and 15 are provided 90 with pins 18; and a ferrule 19, which is rotatable upon the yoke 10 but which is held thereon by a flange 20, is provided with an angular slot 21 adapted to receive the pins 18, and thus provide a bayonet joint for 95 maintaining the fork upon the yoke. In the device disclosed in Figs. 8 and 9, a ferrule 22 having a flange 23 disposed within a groove 24 in the yoke 10 is internally 100

- threaded and adapted to screw upon the threaded fingers 14 and 15 upon the yoke. In this manner, the fork, which engages and compresses the spring S, is detachably secured to the yoke and various sized forks may be employed, depending upon the size of the washer and of the valve spring upon the various internal combustion engines, upon which the device may be applied.
- Upon the upper end of the yoke 10 there is formed a sleeve 25, in which is slidable a spindle 26. The spindle 26 is threaded with threads which are not V threads, as clearly shown in Fig. 4, but have their upper sides substantially horizontal. In this manner the spindle 26, while being a threaded spindle, is also a toothed spindle, having helical teeth formed thereon for a purpose hereinafter to be described. The spindle 26 is slidable within the sleeve 25 and carries upon its upper end a crank 27. Upon the lower end of the spindle 26 there is an engaging member 28 which is held upon the spindle by means of a ball and socket joint 29. About the spindle 26 above the engaging member 28 there is disposed a coil bumper spring 30, and a coil spring 31 is disposed about the spindle above the sleeve 25, and is adapted to be compressed by the sleeve 25 and the crank 27 when the spindle is forced downwardly with respect to the yoke 10.
- An aperture 32 is provided in the sleeve 25 and a pawl 33 is pivoted upon the sleeve 25, which is adapted to extend through the aperture 32 and engage upon the spindle 26 so as to prevent upward movement of the spindle 26 with respect to the yoke. The pawl 33 carries a lever 34 which is urged outwardly by a coil spring 35 so as to resiliently maintain the pawl 33 in engagement with the spindle 26. Below the sleeve 25 a collar 36 is slidable upon the spindle 26. The collar 36 carries a pawl 37 engageable upon the spindle 26, which pawl is shown as pivoted at 38 and is provided with an upwardly extending portion 39 engaged by a spring 40 which urges the pawl 37 into engagement with the spindle 26. This pawl, like the pawl 33, when engaging with the spindle, prevents the upward movement of the spindle with respect to the yoke 10. Upon the sides of the collar 36 there are formed trunnions 41 which pivotally secure the members 42 and 43 of a lever, generally designated at 44, to the collar 36. The members 42 and 43 forming the lever 44 are secured together at their outer ends to provide a handle 45. Extending between the members 42 and 43 there is a pin 46 upon which is rotatably mounted a roller 47. A slot 48 is provided in the yoke 10 and the roller 47 is adapted to roll in the slot. In this manner a traveling fulcrum is provided for the lever 44. The yoke 10 and the sleeve 25 have provided thereon a finger 49 which extends

downwardly and is adapted to engage with the portion 39 of the pawl 37 when the collar 36 is in its uppermost position, so as to disengage the pawl from the spindle.

The operation of the device is as follows: In applying the lifter to an internal combustion engine, the fork 11 is placed beneath the washer W, as shown in Fig. 1. The spindle 26 may then be forced downwardly with respect to the yoke 10 so as to engage upon the top of the valve V or upon any other part of the internal combustion engine. The movement of the spindle 26 is not retarded by the pawls 33 or 37, as these pawls when engaging upon the spindle only prevent its upward movement. When the engaging member 28 is engaging a part upon the top of the internal combustion engine, the lever 44 is reciprocating up and down, causing a reciprocation of the collar 36 upon the spindle 26. Upon the downward movement of the collar 36, the pawl 37 is in engagement with the teeth or the threads provided upon the spindle, and causes the spindle 26 to move downwardly with respect to the yoke 10, thereby raising the fork 11 and compressing the spring S. As the spindle 26 moves downwardly with respect to the yoke 10, it merely slides beneath the pawl 33. Upon the upward movement of the collar 36, the pawl 37 merely slides over the teeth upon the spindle and the pawl 33 maintains the spindle in the position into which it was brought upon the down stroke of the collar 36. After the collar 36 is brought upwardly, it may be again forced downwardly, thereby forcing the spindle 26 downwardly with respect to the yoke 10 and additionally compressing the spring S. When the spring S has been sufficiently compressed, the pin P may be removed from the valve stem V. It will be noted that as the spindle 26 is forced downwardly with respect to the yoke 10, the coil spring 31 will be compressed. After the pin P has been removed, the collar 36 is moved into its uppermost position whereby the upper portion 39 of the pawl 37 engages with the finger 49 so as to disengage the pawl from the spindle. Upon removing the valve spring lifter from the internal combustion engine, the lever 44 is pressed inwardly so as to disengage the pawl 33 from the spindle 26. As the pawl 37 has been disengaged by thrusting the collar 36 into its uppermost position, the spindle 26 becomes slidable in the sleeve 25 and can be lifted therethrough by the coil spring 31. Usually, the coil spring 31 throws the spindle upwardly through the sleeve with a considerable velocity, and to prevent the engaging member 28 from striking the collar 36, the bumper spring 30 is employed. The crank 27 by being rotated causes the spindle 26 to act as a jack screw and provides a fine adjustment for the spindle, which would

not otherwise be provided by the collar 36 and the pawl 37. The engaging member 28 has a universal joint connection with the spindle 26 and can readily accommodate it 5 self to various surfaces against which it may be placed.

From the above it is seen that an improved valve spring lifter is provided, having a number of improvements over my 10 prior device, that I now employ a reciprocating lever for thrusting the spindle downwardly, and that the movement of the spindle is not limited by the throw of the lever.

In the device disclosed in Fig. 12, I have 15 provided an attachment which may be employed for lifting two valve springs simultaneously. This device has fingers 14' and 15' which are mounted upon a cross bar 50. Forks 51 and 52 are detachably secured to 20 the cross bar 50 by wing nuts 53. The fingers 14' and 15' may have apertures therein to receive the thumb screw 17, or may be provided with pins, similar to the pins 18, or may be threaded as the fingers are threaded 25 as shown in Fig. 8.

It will be noted that the crank 27 provides a head upon the spindle 26, which can be struck by a hammer, and such striking frequently loosens the pin or key P when 30 the key or pin is formed of two or more parts as in some types of internal combustion engines.

It will be understood that various changes 35 in the detail of construction may be made without departing from the spirit or scope of the invention as defined by the appended claims.

I claim:

40 1. A valve spring lifter comprising a yoke, means carried by said yoke adapted to engage and lift a valve spring, a sleeve carried by said yoke, a threaded spindle slidable in said sleeve, a spring actuated pawl 45 engageable upon said spindle for preventing upward movement of said spindle with respect to said yoke, means for rotating said spindle, and means for disengaging said pawl from said spindle.

50 2. A valve spring lifter comprising a yoke, means carried by said yoke adapted to engage and lift a valve spring, a sleeve carried by said yoke, a threaded spindle slidable in said sleeve, a pawl engageable upon said 55 spindle for preventing its upward movement with respect to said yoke, a collar slidable upon said spindle, a pawl carried by said collar engageable upon said spindle, means for reciprocating said collar upon said spindle so as to force said spindle downwardly with respect to said yoke, and means engageable upon said pawl upon said collar for disengaging it from said spindle when said collar is in its uppermost position.

60 65 3. A valve spring lifter comprising a

yoke, means carried by said yoke adapted to engage and lift a valve spring, a sleeve carried by said yoke, a toothed spindle slidable in said sleeve, a lever having a fulcrum movable upon the yoke, a collar disposed about the spindle carried by said lever, and pawls pivoted upon said collar and sleeve engageable upon said spindle whereby the spindle may be forced downwardly by said lever, collar and pawl carried thereby and held in such position by the pawl on said sleeve. 70 75

4. A valve spring lifter comprising a yoke, means carried by the yoke adapted to engage and lift a valve spring, a sleeve carried by the yoke, a toothed spindle slidable in the sleeve, a lever, a roller carried by the lever adapted to roll upon said yoke, a collar slidable upon said spindle pivoted to the lever, and pawls mounted on said collar and sleeve engageable upon the spindle, whereby the lever may cause the spindle to move downwardly with respect to the yoke and the spindle may be held in such position by the pawl on said sleeve. 80 85 90

5. A valve spring lifter comprising a yoke, means carried by the yoke adapted to engage and lift a valve spring, a sleeve carried by the yoke, a toothed spindle slidable in the sleeve, a lever, a roller carried by the lever adapted to roll upon said yoke, a collar slidable upon said spindle pivoted to the lever, pawls mounted on said collar and sleeve engageable upon the spindle, a head upon the upper end of the spindle, and a coil spring disposed about the spindle between the head and the sleeve, the lever being so arranged that it may cause the yoke to move upwardly relatively to the spindle in which position it may be held by the pawl on said sleeve. 95 100 105

6. A valve spring lifter comprising a yoke, means carried by the yoke adapted to engage and lift a valve spring, a sleeve carried by the yoke, a toothed spindle slidable therein, a pawl pivoted on the sleeve engageable on the spindle, a lever having a fulcrum movable on the yoke, a collar pivoted to said lever, and a pawl pivoted to the collar engageable on the spindle, whereby the lever may be oscillated to cause the collar and pawl thereon to move the spindle downwardly with respect to said yoke, the first mentioned pawl serving to prevent upward movement of the spindle relatively to the yoke while the collar is being moved upwardly thereon. 110 115 120

7. A valve spring lifter comprising a yoke, means carried by the yoke adapted to engage and lift a valve spring, a sleeve carried by the yoke, a threaded spindle slidable therein, a pawl pivoted on the sleeve engageable on the spindle, a lever having a fulcrum movable on the yoke, a collar pivoted to said lever, a pawl pivoted to the 125 130

- collar engageable on the spindle whereby the lever may be oscillated to cause the collar and pawl thereon to move the spindle downwardly with respect to said yoke, the first 5 mentioned pawl serving to prevent upward movement of the spindle relatively to the yoke, while the collar is being moved up-

wardly thereon, there being a crank mounted on top of the spindle, and a coil spring disposed between said sleeve and crank as 10 and for the purpose described.

In testimony whereof I have signed my name to this specification.

LOUIS H. BAYLER.
